CLAIM

The ornamental design for a child's doll figure or similar article, as shown and described.

DESCRIPTION

FIG. 1 is a front elevational view of a child's doll figure or similar article structure embodying our new design;

FIG. 2 is a rear elevational view thereof;

FIG. 3 is a side elevational view thereof;

FIG. 4 is a side elevational view of the other side thereof;

FIG. 5 is a top plan view thereof;

FIG. 6 is a bottom plan view thereof;

FIG. 7 is a front elevational view of a second embodiment of the child's doll figure or similar article embodying my new design;

FIG. 8 is a rear elevational view of the second embodiment;

FIG. 9 is a side elevational view of the second embodiment;

FIG. 10 is a side elevational view of the other side of the second embodiment;

FIG. 11 is a top plan view of the second embodiment; and

FIG. 12 is a bottom plan view of the second embodiment.
